UNITED STATES PATENT OFFICE

172,507

AIRPLANE OR SIMILAR ARTICLE

Henri J. Myser, Mount Vernon, Ill.

Application August 10, 1953, Serial No. 26,393

Term of patent 14 years

(Cl. D34—15)

To all whom it may concern:

Be it known that I, Henri J. Myser, a citizen of the United States, residing at Mount Vernon, Jefferson County, State of Illinois, have invented a new, original, and ornamental Design for an Airplane or Similar Article, of which the following is a specification, reference being had to the accompanying drawing, forming a part hereof.

Fig. 1 is a top plan view of an airplane or similar article, showing my new design;

Fig. 2 is a side elevational view thereof; and

Fig. 3 is a bottom plan view thereof.

The dominant features of my new design are shown in solid lines in the drawing.

I claim:

The ornamental design for an airplane or similar article, substantially as shown and described.
